W. G. KENDALL.
ROUGE BOX.
APPLICATION FILED AUG. 5, 1915.

1,194,187.

Patented Aug. 8, 1916.

UNITED STATES PATENT OFFICE.

WILLIAM G. KENDALL, OF NEWARK, NEW JERSEY.

ROUGE-BOX.

1,194,187.

Specification of Letters Patent.

Patented Aug. 8, 1916.

Application filed August 5, 1915. Serial No. 43,813.

To all whom it may concern:

Be it known that I, WILLIAM G. KENDALL, a citizen of the United States, residing at Newark, in the county of Essex and State of New Jersey, have invented certain new and useful Improvements in Rouge-Boxes, of which the following is a specification.

My present invention relates to new and useful improvements in receptacles or containers and more particularly to rouge boxes, the primary object of my invention being the provision of a rouge box in which the rouge holding pad, instead of being attached directly to the bottom of the box, is indirectly secured to the box in such a manner as to be yieldably held at the top of the box when the latter is opened and, therefore, in such a manner that the rouge is readily accessible at all times.

20 In this connection, a still further object of my invention consists in providing a rouge box having a false bottom serving as an anchoring means for a supporting spring, the upper end of which is secured in any suitable manner to the bottom of the rouge holding pad.

A still further object of my invention consists in providing a container of the above described character including an outer box 30 and an inner box, the latter having the false bottom and being proportioned to closely encircle the pad.

A still further object of my invention consists in the provision of a box so proportioned that a rouge puff may be contained in the box above the rouge pad when the box is closed, and in the provision of a mirror in the top of the box which is exposed when the box is opened.

40 With these and other objects in view, my invention will be more fully described, illustrated in the accompanying drawings, and then specifically pointed out in the claims which are attached to and form a part of 45 this application.

In the drawings: Figure 1 is a perspective view of my improved rouge box, the box being shown opened and the rouge in raised position; Fig. 2 is a central, vertical sectional view taken through the box in closed position; Fig. 3 is a top plan view of the box without the rouge, the cover of the box not being shown in this figure; Fig. 4 is a perspective view of the bottom of the rouge holding pad and its supporting spring, showing the manner of connecting the two; Fig.

5 is a sectional view corresponding to that shown in Fig. 2, illustrating a modified form of box construction; Fig. 6 is a vertical sectional view of a modified form of rouge holding pad, showing a different way of attaching the spring to the bottom of the pad.

60 Corresponding and like parts are referred to in the following description and indicated in all the views of the drawings by the same reference characters.

In that form of my invention illustrated in Figs. 1 to 4 of the drawings, I employ an outer box 10 having a cover 11 and inclosing an inner box 12 in which the rouge pad 13 is 70 positioned, being supported therein by a spring 14.

More specifically, the outer box includes a bottom 15, of any desired shape, formed with an upstanding marginal wall 16 which forms 75 the outer wall of the outer box. An upstanding inner wall 17 is secured within the box, engaging at its outer face against the inner face of the outer wall 16 and projecting at its upper edge above the upper edge 80 of the outer wall in such a manner that the outer wall will form a stop for the cover, as will be later explained. The cover 11 includes the top proper 18 having the downwardly depending marginal flange 19, the 85 free edge of which engages the upper edge of the outer wall 16 of the outer box when the cover is closed. A strip of fabric or other suitable material 20 serves to hingedly connect the cover to the box, one end of this 90 strip being secured between the inner and outer walls 16 and 17 and the opposite end being secured to the outer face of the marginal wall 19 of the cover. The cover and box are both covered with paper or other 95 suitable material for the purpose of ornamentation and secured within the cover and against the inner face of the top portion 18 thereof, is a mirror 21, a retaining strip 22 of paper or other suitable material, secured 100 to the marginal wall 19 and to the peripheral edge of the mirror, serving to hold the latter in place.

The inner box includes an annular bottom proper 23 and an annular false bottom 24, 105 the opening in the false bottom being concentric with, but considerably smaller than the opening in the bottom 23. Both of these bottom members are secured to a peripheral or marginal wall 25 which is generally 110 slightly less in height than the height of the wall 17 of the outer box. This inner box is

generally cylindrical in shape in order that it may closely encircle the rouge holding pad 13. This rouge holding pad forms the subject matter of a separate application filed 5 by me June 14, 1915, and bearing the Serial No. 34,303 and need not, therefore, be described in detail in this case.

The pad consists of a circular body, generally of sheet metal having an upwardly 10 and inwardly directed annular retaining flange 26 and the rouge 27 is pressed onto the upper face of the pad in the manner shown and retained in place by this flange.

Secured to the bottom of the pad 13 and 15 centrally thereof, is a retaining ring 27', generally formed of wire in order to provide an undercut shoulder to receive the smaller end of the tapering helical spring 14. The opposite or lower larger end of this spring 20 is retained by being partially threaded through the opening in the false bottom 24, the portion passing through this opening seating within the opening of the bottom proper of the inner box.

25 In assembling the above described article, the spring is attached to the pad and then threaded into the false bottom of the inner box, after which the inner box is positioned within the outer box and secured in place by 30 adhesive or any other suitable means desired. The spring 14 is of such strength and so proportioned as regards its length as to normally support the pad in the position shown in Fig. 1, that is, with the rouge at least 35 level with the top of the inner box. The spring may, however, be compressed to permit the keeping of a rouge puff 28 between the cover of the box and the pad in the manner shown in Fig. 2.

40 In Fig. 5 of the drawings, I have illustrated a simpler form of construction including the outer box 10' and its cover 11' which are identical with the box and cover 10 and 11 previously described, except that 45 they are proportioned to snugly receive the rouge holding pad 13. In this form of the invention, a false bottom 29 is secured within the box in spaced relation to the true bottom 15 thereof and is formed centrally with an 50 opening to receive the lower end of the supporting spring 14.

In place of the retaining ring 27, soldered or otherwise secured to the bottom of the rouge pad, I may provide a structure such 55 as that shown in Fig. 6 in which the bottom of the rouge pad is upstruck to provide an annular seat 30, the peripheral faces of which converge downwardly in order that the seat may be narrower at its lower than at 60 its upper end. This seat, in itself, receives

the upper end of the supporting spring 14 and the spring is retained by engagement with the inclined annular walls of the seat.

In view of the different constructions above illustrated, it will be clear that I do 65 not wish, in any way, to limit myself to the specific arrangement of parts set forth and illustrated, as various minor changes, within the scope of the appended claims, may be made at any time, without in the slightest 70 degree departing from the spirit of my invention.

Having thus described the invention, what is claimed as new is:

1. A rouge package including a box having 75 a hinged cover, a false bottom within the box and spaced from the bottom thereof and provided with an opening, a rouge pad within the box, and a helical spring having one convolution passed through the opening 80 in the false bottom and anchored beneath the bottom, the spring being connected at its opposite end to the rouge pad.

2. A rouge package including an outer box having a hinged cover, an inner box positioned within the outer box with its bottom spaced above that of the outer box and provided with an opening, a rouge pad formed with an annular undercut shoulder upon its bottom, and a helical spring having a terminal convolution sprung under the shoulder and with its other end passed through the opening in the false bottom. 85 90

3. A rouge package including a box having 95 a true and a false bottom spaced apart, the false bottom being formed with an opening, a helical spring having one end passed through the opening and anchored below the false bottom, a rouge pad positioned in the box, and a ring of wire secured to the lower 100 face of the rouge pad to engage the upper end of the spring.

4. A rouge package including a box having 105 a hinged cover, an inner box centrally disposed in the first box with its peripheral wall spaced from the walls of the first box, the second box having a double bottom formed centrally with openings, the opening in the upper bottom being more reduced than that in the lower bottom, a rouge pad 110 fitting within the inner box and guided by its wall, and a helical spring connected at one end to the bottom of the pad and having a terminal convolution passed through the smaller opening of the upper bottom member of the inner box. 115

In testimony whereof I affix my signature.
WILLIAM G. KENDALL. [L. s.]
